(57) **CLAIM**

The ornamental design for a foldable table and cutting board, as shown and described.

DESCRIPTION

FIG. 1 is a perspective view showing a front, top and right side of a foldable table and cutting board embodying our design, with the cutting board in a stowed position.

FIG. 2 is a perspective view showing rear, bottom and left side thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is a perspective view showing a front, top and right side of the foldable table and cutting board of FIGS. 1-9 with the cutting board in an extended position.

FIG. 10 is a perspective view showing rear, bottom and left side thereof.

FIG. 11 is a front view thereof.

FIG. 12 is a rear view thereof.

FIG. 13 is a right side view thereof.

FIG. 14 is a left side view thereof.

FIG. 15 is a top view thereof.

FIG. 16 is a bottom view thereof.

FIG. 17 is a perspective view showing a front, top and right side of the cutting board shown separately for ease of illustration.

FIG. 18 is a perspective view showing rear, bottom and left side thereof.

FIG. 19 is a front view thereof.

FIG. 20 is a rear view thereof.

FIG. 21 is a right side view thereof.

FIG. 22 is a left side view thereof.

FIG. 23 is a top view thereof; and,

FIG. 24 is a bottom view thereof.

The broken lines in the drawings illustrate portions of the foldable table and cutting board which form no part of the claimed design.

1 Claim, 19 Drawing Sheets
